COIN SLIDE

Walter A. Tratsch, Chicago, Ill.

Application June 7, 1937, Serial No. 146,836

12 Claims. (Cl. 194—97)

This invention relates to coin-freeed control mechanisms commonly referred to as coin slides, and has among its important objects the provision of an improved frame structure, slide mechanism and operating means therefor, together with novel fraud-preventive devices cooperable with the slide mechanism, and also an improved form of discharge chute.

More specifically stated, one of the important objects of the invention is the provision of a guide frame having a coin-receiving or deposit opening and a discharge opening spaced therefrom, a coin slide mounted for reciprocable movement in the frame, and manually operable push bar mechanism for reciprocating the slide so as to move a coin-receiving pocket in the latter from the coin deposit opening toward the discharge opening in the frame.

A further object is the provision with a slide frame of the type just described of a drop-out pocket adjacent the deposit pocket in the frame and into which a coin deposited, after the coin slide has been moved in, will be moved by the slide upon its return stroke to be returned to the depositor.

Still another object is the provision of fraud-preventive means in the form of a cut-off pawl arranged to be positively cammed by the coin slide for movement into position behind the end of the slide after the latter has moved a predetermined distance in its operating stroke.

Yet another object is the provision of fraud-preventive means in the form of a gauge dog structurally related to the aforesaid cut-off device or pawl and operable to latch the slide against movement responsive to engagement by this gauge pawl with a coin of improper thickness.

Yet another object is the provision of a discharge chute and auxiliary slide means cooperable with the main coin slide for regulating the movement of coins into the discharge chute, the latter being provided with pawl mechanism adapted to sweep coins released from the auxiliary slide means and move such coins step by step along the discharge chute.

Other novel aspects of construction and operation of the invention reside in the form and arrangement of parts to be hereinafter particularly described and claimed in view of the annexed drawings in which:

Fig. 1 is a top plan view of the complete slide unit;

Fig. 2 is a slightly enlarged vertical section 55 along lines 2—2 of Fig. 1;

Fig. 3 is a bottom plan view of the device of Fig. 1;

Fig. 4 is a slightly enlarged vertical section along lines 4—4 of Fig. 1 showing a portion of the juncture of the discharge chute with the main slide unit;

Fig. 5 is a vertical median section through the main frame and slide unit as viewed along lines 5—5 of Fig. 1;

Fig. 6 is an enlarged perspective fragment, 10 viewed from the front, of the gauge pawl and coin slide;

Fig. 7 is an enlarged perspective fragment, viewed from the rear, of both the gauge pawl and the cut-off pawl;

Fig. 8 is a vertical section similar to part of the structure of Fig. 5 showing the gauge pawl and gate pawl in partly operative position;

Fig. 9 is a fragmentary vertical section duplicating parts of Figs. 8 and 5 and showing the 20 pawls and slide in full operative position; while

Fig. 10 is an enlarged perspective detail of a portion of the discharge chute and discharge pawl mechanism.

In general the novel coin slide unit includes, 25 as viewed in Fig. 1, a main frame in the form of a horizontally extended casting having a vertically extending mounting plate or wall 12 dividing the frame into a front or depositing section 13 and a rear section 14 in which is slidably 30 mounted a main coin slide 15 having a pair of spaced coin apertures 16 and 17, the former being situated close to the front or left-hand extremity of the slide and being normally disposed in registration with a coin deposit opening 18 in the front section 13 of the main frame. Operating mechanism including a push bar or actuating slide 19 is provided to reciprocate the slide 15 so as to move a coin, deposited through the depositing opening 18 into the slide pocket 40 16, beneath the mounting plate 12 and past certain fraud-preventive dogs toward a discharge opening 20 (Fig. 5 also) situated below the normal position of the innermost or right-hand 45 coin-viewing aperture 17 in the slide 15. Secured to the main frame so as to extend therefrom in a lateral direction is a discharge chute 22 provided with mechanism, operable by actuation of the slide, for moving coins in step by step fashion toward the discharge end of the chute. 50

As viewed in Figs. 3 and 5, the slide actuating mechanism 19 includes a pair of spaced push rods 23 and 23' joined at one end by the push member 19 and at their opposite or inner end by a cross bar 24 suitably secured to the inner ends 55

- of the rods. The spaced rods 23 and 23' are slideable in the lower portion 12' of the vertical mounting plate or wall 12 and also in staggered lugs 25 depending from the inner body of the frame. A coil spring 26, anchored at one end 27 to the frame and attached at its opposite end 28 to the cross bar 24, normally urges the push bar actuating member 19 into its normal position, as viewed in Figs. 3 and 5.
- 10 At its rearward end, the main coin slide 15 is rigidly connected to the push rod structure 19 by means of an angled extension 29 of the cross bar 24 which is secured to the slide by the pin means 30. As before stated, the slide 15 is seated in grooved formations 31 (Fig. 2) in the main rear frame extension 14 and is slideable through an opening 32 in the mounting plate 12 into a grooved portion of the forward extension 13 of the frame, so as to position the coin-receiving or depositing hole 16 in slide 15 beneath the coin depositing opening 18 in the frame, this latter condition being represented by the normal disposition of the slide in Fig. 5. There is underlying the registered deposit openings 16 and 18 of the slide and frame, respectively, a portion 33 of the frame which provides a bottom or ledge on which the deposited coin rests to be carried with the slide 15 inwardly when the latter is moved by the push bar structure 19.
- 30 Formed in the underside of the front ledge extension 13 of the frame is a novel form of drop-out opening 34 communicating with the deposit opening 18 interiorly of the casting (see also Fig. 3), and extended from the juncture of the drop-out opening 34 with the depositing pocket 18 is an elongated slot 35 which leads back through the bottom ledge portion of the slide seat in the frame into a depressed shelf portion 36 formed in the frame below the slide 15 and onto which a coin will gravitate out of the aperture 16 in the slide when the latter is moved inwardly. At the outer or left-hand end of the slide 15 is a depending ear or lug 37 (Figs. 3 and 5) which moves in the elongated slot 35 from its normal position, as viewed in Fig. 5, to the full stroke position as viewed in Fig. 9, the purpose of this lug being to engage the edge of a coin 38 as it falls onto the shelf 36 out of the pocket in the slide so as to shove the coin along 50 toward the discharge opening 20 in the frame to the rear or at the right of the shelf 36. There is also provided a depending lug 40 positioned on the opposite side of the coin opening or pocket 16 in slide 15 and extending into the elongated 55 frame slot 35 so as to block the latter against the insertion of fraudulent operating devices, such as wires and the like, when the slide is in its normal position.
- Extending longitudinally from the front coin pocket 16 in slide 15, is a slot or channel 41 which communicates with the rear sight opening 17 in slide 15 and which also has an extension 41' projecting somewhat beyond the rear opening 17 (Figs. 1, 2 and 7).
- 60 65 Slidably mounted below the rear extension 14 of the main frame is a reciprocable auxiliary slide 39 having a coin discharge opening 39' through which a coin moving into the discharge opening 20 may descend onto the floor 42 of a discharge chute later to be described in detail.
- The auxiliary slide 39 has a depending lug 43 to which is attached one end of a spring 44 anchored on an ear 45 attached to the discharge chute 42 (Figs. 3, 5 and 9) whereby the auxiliary 70 slide is normally urged toward the left and into

a normal position as seen in Fig. 5 wherein the opening 39' thereof is in register with the sight opening 17 in slide 15.

However, when the coin slide 15 is moved into its full stroke position as seen in Fig. 9, the auxiliary slide is moved therewith so that a portion 39' blocks the discharge opening 20 in the frame and serves to hold a coin 38 therein until the main coin slide is returned to normal position. This is accomplished by means of a pin 46 which 10 projects upwardly from the rear of the auxiliary slide 39 into the rearward extension 41' of the longitudinal slot 41 in the main slide 15, there being a shoulder formation 47 (Fig. 1) at one side of this slot or channel which bears against 15 the pin 46 when the slide is moved inwardly a predetermined distance, so that thereafter the main slide and the auxiliary slide move together for the remainder of the stroke.

Slidably mounted on the floor of the discharge chute casting 42 (Fig. 10) is a coin-feeding cam 48 pivotally connected as at 49 (see also Fig. 9) to the auxiliary slide 39 for movement with the latter. This feeding pawl 48 has an irregular slot 50 formed therein and in which is received 25 an upstanding pin 51 on the floor of the chute 42 and which is effective, when the pawl is moved back and forth with the auxiliary slide 39, to pivot the pawl back and forth about the pivotal point 49 so as to cause the nose portion 52 of the pawl to sweep back and forth from the dotted line to the full line position illustrated in Fig. 10 for the purpose of sweeping or pushing a coin 38 lying on the floor of the chute 42, onto which it has been previously discharged from the discharge opening 20 in the main frame, toward and past a plurality of presser fingers in the form of springs 53 attached to the bottom of the discharge chute 42 and protruding into the chute through bottom wall openings 54.

The chute generally indicated at 22 in Figs. 1 and 3 includes the main frame portion 42, above referred to, and which is adapted to be removably attached to the bottom of the main guide frame by screws or other suitable means 55. This bottom member of the discharge chute is preferably in the form of a die casting and has an elongated coin channel 56 formed therein communicating with an enlarged head portion in which the sweeping or feeding pawl 48 is seated, at the 30 point where the presser fingers 53 are situated.

At the opposite end 57 of the discharge chute, the coin channel 56 is open so that coins may pass from the latter into any desired receptacle. Intermediate the end 57 and the head portion 55 of the chute is an elongated drop-out opening 58 through which coins of less than a predetermined diameter are intended to pass for rejection.

Still referring to Fig. 1, it will be seen that there is provided a U-shaped presser member 59 60 having its opposite side arms 60 seated in slots formed in the side wall portion of the chute extension 22, the ends 61 of these arm portions being bent back toward one another to prevent the disengagement of the presser from the slots.

Between the inner surface of the presser 59 and the opposite wall portion of the chute body is a spring 62 which normally tends to project the main body of the presser into the channel portion 56 of the discharge chute and slightly beyond the 70 edge of the drop-out opening 58; thus proper coins or tokens will be carried over the drop-out opening 58 by the suspension of the coin in yieldable pressing engagement with the presser bar 65 75 and the opposite wall of the chute passage, 75

- 75

while improper coins or tokens of less than a determined diameter will drop directly through the opening 58. It will be apparent that a plurality of coins 38 (referring now to Figs. 1 and 10) will collect in the chute 22 between the discharge end 57 and the head portion thereof and that as each coin 38 drops onto the floor of the discharge chute the pawl nose 52 will move the coin into the chute proper, each subsequently deposited coin engaging the one previously deposited and serving to move the latter along in step by step fashion. There is further provided a cover plate 63 for the chute extension 22 and attached to the latter by means of screws 64. This plate 15 has an elongated opening 65 through which the coins distributed in the chute may be viewed.

The important fraud-preventive means provided by the invention includes a cut-off dog or pawl 70 pivotally mounted as at 71 (Figs. 1 and 7) on the frame above the slide 15, and having a depending nose portion 72 substantially of the same width as the slide and disposed laterally across the path of movement of the same. Formed beneath the slide 15 in the main frame 25 and behind or to the right of the mounting wall 12 thereof is a lateral recess or depression 73 into which the laterally extending nose portion 72 of the stopping dog descends when the slide 15 has been moved in full stroke position as illustrated 30 in Fig. 9 so as to completely block the opening 32 in the wall portion 12 and cut off any access to the mechanism through the deposit opening 18 and the wall 12.

The cut-off or stopping dog 70 is normally urged by means of a spring 74 into lowered position with the lateral depending nose portion 72 thereof in a normal position bearing down on the slide 15, notches 72' being provided at opposite extremities of the nose edge 72 so that the latter may fit closely down between the longitudinal side flanges of the slide. The pawl 70 is provided at its end opposite the nose portion 72 thereof with a cam portion 75 overlying a side edge portion of the slide 15 and engageable by a cam rise or flange 76 on the side of the slide when the latter is moved a predetermined distance inwardly, that is to say a distance corresponding closely to the approach of the outer axial end portion of the slide 15 (at which the depending lug 37 is situated) just beneath the depending nose 72 of the cut-off pawl 70, the cam portion 76 on the slide by its engagement with the cam extension 75 on the pawl serving positively to pivot the pawl forcibly downward so as to cause the nose 72 thereof to descend over the retreating edge portion of the slide 15 as the latter moves into full stroke position, thereby completely blocking any access to the operating mechanism through the opening 32 in the frame.

The cut-off pawl 70 is substantially constructed, and the mechanical advantage in the cam arrangement is such as will provide a considerable leverage so that should any device such as a wire or feeler ribbon or the like be attached 65 to a coin or be inserted in the slide or lie in the path of the descending movement of the nose 72 of the pawl, the force of descent of the latter will be adequate in most instances to shear the feeler or wire, or substantially deform the same so 70 as to render the fraudulent attempt wholly unsuccessful, in addition to preventing any further possibility of access to the mechanism so long as the pawl remains cammed in blocking position by the slide 15. As soon as the slide 15 is 75 retracted and the cam rise or flange 76 passes

out of engagement with the cam 75 of the pawl, the latter will be urged by the spring 74 back into the position wherein the cut-off dog 70 bears down on the slide 15; and when the slide 15 is likewise in normal position, the depending ear 5 40 thereon will adequately block the passage 32. It will also be observed that the pawl 70 must be moved into effective position whenever the slide 15 is moved a predetermined distance, regardless of whether there is a coin in the slide or not. 10

A further fraud-preventive mechanism is provided in the form of a gauge pawl 77 (Figs. 1, 6, and 7) pivotally mounted as at 78 on the frame above the slide 15 adjacent the pawl 70. This gauge pawl has an angled end portion 79 from 15 which depends a finger 80 positioned above the slide 15 in the path of movement of the coin-receiving or bearing aperture 16 thereof, so as to engage a coin in the latter as the slide is moved inwardly, and this finger 80 extends downwardly 20 in a slot 88 cut in the pawl 70 between the nose portion 72 and the pivoted side of the same. Likewise depending from the main body portion of the pawl 77 is a latching finger 81 which is movable into an edgewise slot 82 formed in the longitudinal edge of slide 15 at one side of the coin opening 16. The gauge pawl or dog 77 is normally urged in a descending direction toward the slide 15 by means of a spring 83, and if there is no coin in the opening 16, as the slide moves the latter beneath feeler finger 80, the pawl will be pivoted downwardly by the spring 83 to project the finger 81 thereof into the notch 82 of the slide and prevent the further inward movement of the latter. It may be observed that the lower extremity of the feeler finger 80 lies in alignment with the longitudinally extensive opening or slot 41 in slide 15, thus providing for free movement of the slide while at the same time the nose of the feeler 80 may descend the required 40 distance into the opening 16 should there be no coin in the latter. 25

A further fraud-preventive instrumentality is provided in the form of a permanent magnet 84 mounted by bracket means 85 on the rear frame 45 section 14 with its pole faces arranged above the slide 15 close to the opposite edge portions of the coin opening 16 so as to attract a magnetic token in the latter and raise the same from the slide a distance adequate to cause the advancing edge 50 of the coin so raised to bear against a depending lug 86 just above the free edge of the shelf 36 in the frame, and thus lock the slide against further effective movement. 55

Having thus illustrated my invention by describing in detail a preferred embodiment and arrangement of parts in realizing the several objects heretofore recited, it is to be understood that all equivalent constructions, modifications, and variations of the foregoing particularly described structure are intended to be embraced by the appended claims. 60

Having thus described my invention, what I claim as new and desire to protect by Letters Patent is: 65

1. A coin slide including a frame having a coin deposit opening and a coin discharge opening, a slide having a coin receptacle and mounted for reciprocable movement in said frame to position said coin receptacle to receive a coin from said deposit opening and move said coin toward said discharge opening for movement into the latter, means for reciprocating said slide, and fraud-preventive mechanism including a cut-off pawl 70 pivoted by said slide into blocking position be- 75

hind an end of the same when the slide and coin receptacle thereof are moved a determined distance toward said discharge opening, whereby to prevent passage of defrauding tools through said frame beyond said cut-off pawl.

2. In a device of the class described including a guide frame having a coin deposit opening, a coin slide mounted in said frame for reciprocable movement and having a coin-receiving pocket to receive coins from said deposit opening, slide reciprocating means mounted on said frame, the latter having a discharge formation in which a deposited coin is received from said slide, the combination of fraud-preventive mechanism in the form of a cut-off pawl mounted for pivotal movement on said frame above said slide and having a wide edge portion movable in a direction laterally across the plane of movement of said slide, said pawl having a cam formation, said slide having a cam rise engageable with the cam formation of said pawl and operable to pivot the latter in timed relation with the movement of said slide and said coin aperture thereof toward said coin-receiving formation in the frame so as to cause said edge portion of the pawl to descend in shearing fashion in a direction across the end of said slide as the latter approaches a predetermined position with reference to said coin-receiving formation whereby access to said slide may be blocked with respect to said frame through said coin deposit aperture thereof.

3. In a coin freed control device of the type having a guide frame and a coin slide reciprocable in a slide opening therein to alternately receive and deposit a coin, a cut-off pawl mounted on said frame above said slide and having a nose portion extended in a direction laterally across the width of said slide and said slide opening and in a position to overlie a particular end of said slide when the same is in coin-depositing position, and means on said slide engageable with said pawl, as the slide approaches coin-depositing position, to move said pawl and urge the said nose portion thereof down across said particular end of the slide into a position to block fraudulent access to the slide through said frame.

4. In a device of the class described including a frame structure comprising an elongated frame member having a transverse mounting plate between its ends and having a coin-receiving pocket in the frame member on one side of the mounting plate, a coin-bearing slide mounted for reciprocation on said frame member and having a coin pocket between its ends and movable by reciprocation of the slide into and out of registration with said coin-receiving pocket in the frame, said slide having a particular end portion movable away from said coin-receiving pocket through a passage beneath said mounting plate when the slide is moved into a predetermined position, and means for reciprocating the slide, the combination of fraud-preventive means comprising: a dog mounted for pivotal movement about an axis transverse of the slide and having a nose portion extending a distance substantially the width of the slide, and coacting cam means on said dog and said slide for moving the dog to project said nose portion behind said particular end of the slide when the latter is moved into said predetermined position whereby to prevent access of defrauding tools to said slide by passage through said coin-receiving pocket and beneath said mounting plate.

5. In a device of the class described, the combination with a reciprocable coin-bearing mem-

ber movable in a guide, of fraud-preventive means comprising a dog arranged for coaction with said coin-bearing member for movement by the latter to project a portion of the dog in blocking position opposite an end of said coin-bearing member when the latter is moved into a predetermined position in the guide, whereby to block access of defrauding instrumentalities to said coin-bearing member from said end thereof through said guide.

6. In a coin-testing device, the combination with a reciprocable coin-bearing slide movable through an opening in a guide, of fraud-preventive means cooperable with said slide and including a dog and means mounting the same for pivotal movement about an axis transverse to the direction of movement of the slide, and coacting cam means on said dog and slide for pivoting the dog to project a portion thereof in obstructing position relative to an extremity of the slide when the latter is moved into a predetermined position to prevent access of defrauding means to said extremity through said opening in the guide.

7. A coin testing device having, in combination, a frame, a coin-bearing slide reciprocable from a coin receiving to a coin depositing position through an opening in said frame, and fraud-preventive means cooperable with said slide and including a dog and means mounting the same for movement to project a portion thereof in blocking position between said opening in the frame and an end portion of the slide when the latter is moved into a predetermined position, and cam means on said slide and engageable with said dog to move the latter into blocking position when the slide is moved into said predetermined position.

8. The combination with a coin testing device including a mounting frame and a coin-transporting member movable in said frame between coin receiving and coin depositing positions, of fraud-preventing means comprising means coacting with the coin-transporting member when the latter moves into a certain position between the coin receiving and depositing positions thereof for blocking access to the latter of a defrauding instrumentally moved in a direction to follow the coin-transporting member in the movement thereof toward coin depositing position.

9. The combination with a coin testing device of the type which includes a coin-transporting slide movable back and forth from a coin receiving to a coin depositing position through a passage in a partition member, of fraud-preventing means comprising: a blocking member arranged and constructed for coaction with said slide to move into a position to block access of a defrauding instrumentality to said slide through the passage in said partition member when the slide has been moved to a predetermined position toward coin depositing position.

10. In a device of the class described, the combination with a coin-transporting member arranged for movement back and forth in a guide opening between a coin receiving and a coin discharging position, of fraud-preventive means including a member arranged for coaction with said coin-transporting member for movement by the latter from a normal ineffective position at one side of the slide in shearing movement in a direction closely across an extremity of said transporting member when the latter has moved a predetermined distance from coin receiving toward coin discharging position, said member being of a size to block said opening when the transporting

member is in coin discharging position as aforesaid.

11. In a device of the class described, the combination with a reciprocable coin-transporting slide which moves through a passage from a coin receiving to a coin discharging position, of fraud-preventive means including a dog and means coacting with the slide arranged for forcibly urging the same from a normal unobstructing position 10 into a position to obstruct access of defrauding means to said slide through said passage when the slide has been moved substantially into coin discharging position.

12. In a device of the class described which includes a coin-transporting slide reciprocable through a confined passage between a coin re-

ceiving and a coin discharging position, means for preventing the manipulation of defrauding instrumentalities relative to said passage and a coin carried by the slide toward discharging position, said means comprising a dog mounted at one side 5 of the slide for movement from a normal ineffective position in shearing action in a direction closely across an end of said slide as the latter approaches said coin discharging position, spring means normally urging said dog into normal position, and coacting means on said slide and dog for moving the dog in shearing action as aforesaid into a position to block access to said end of the slide through said passage. 10
